(57) **CLAIM**

The ornamental design for a modular table, as shown and described.

DESCRIPTION

1. Modular table

2. Set of modular tables

1.1: is a left view of the first embodiment of a modular table, showing my new design

1.2: is a left view thereof shown in a folded position

1.3: is a front view of 1.1

1.4: is a back view thereof

1.5: is a right side view thereof

1.6: is a top view thereof

2.1: is a left view of the second embodiment of a set of modular table, one of the components isolated for clarity of illustration

2.2: is a back view thereof

2.3: is a right side view thereof

2.4: is a front view thereof

2.5: is a perspective view of a set of modular table

2.6: is a perspective view thereof in an alternate position

(Continued)

2.7: is a perspective view thereof in another alternate position

1 Claim, 13 Drawing Sheets
